Primary Examiner — Kimberly Barnes*(74) Attorney, Agent, or Firm* — Michael Bartholomew(57) **CLAIM**

The ornamental design for a cleaning brush as shown and described.

DESCRIPTION

FIG. 1 is a perspective view of a cleaning brush showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is another perspective view showing the cleaning brush in use.

The broken lines in FIG. 9 illustrate environmental subject matter when the cleaning brush is in use, and forms no part of the claimed design.

1 Claim, 9 Drawing Sheets(56)
